US00D630442S

(12) United States Design Patent
Sichel

(10) Patent No.: US D630,442 S
(45) Date of Patent: * Jan. 11, 2011

(54) FABRIC

(75) Inventor: Graham Sichel, Cheshire (GB)

(73) Assignee: Bentley Motors Limited (GB)

() Term: 14 Years

(21) Appl. No.: 29/360,148

(22) Filed: Apr. 21, 2010

(30) Foreign Application Priority Data

Oct. 24, 2009 (EP) 001175053-0002

(51) LOC (9) Cl. 05-05

(52) U.S. Cl. D5/60; D5/57

(58) Field of Classification Search D5/1-8,
D5/11-14, 16, 18-20, 23-27, 30, 32, 34,
D5/37, 39-43, 46-50, 52-54, 56-61, 63-65,
D5/66, 99; D6/582-587, 589, 612, 613,
D6/615-617, 621-623; D11/165, 167, 168,
D11/170, 171, 173, 174; D19/5-8; D20/22,
D20/26, 27, 28, 36; D24/124-126; 4/581;
5/420; 15/215; 52/660; 66/169 R, 190,
66/202; 112/400-402; 139/383 R, 420 R,
139/424; 162/109, 134; 428/15-17, 32,
428/32.16, 32.21, 39, 66.5, 187, 221, 906.6
